SOUND RECORDING APPARATUS

Herbert Belar, Philadelphia, Pa., assignor to Radio Corporation of America, a corporation of Delaware

Application December 28, 1940, Serial No. 372,199

5 Claims. (Cl. 179—100.3)

This invention relates to sound recording apparatus and more particularly to a ground noise reduction amplifier for use in conjunction with such apparatus.

In photographic sound recording apparatus as now used commercially, the clear portion of the film around the sound track is usually obscured by an appropriate masking or envelope record which prevents the transmission of unnecessary light through the film, while with variable density records the average exposure is varied to accomplish the same result.

In the production of such a record, an amplifier is used which amplifies and rectifies the voice currents so as to produce a direct current of variable amplitude corresponding to the volume of the sound to be recorded and this envelope current is used in turn to control the shutters, galvanometer or light valve, as the case may be.

In such amplifiers, as heretofore constructed, there has been utilized an audio frequency amplifier which functions to bring the audio frequency input to the proper level and is followed by a rectifier and a filter. The rectified and filtered current is then used to control a D. C. amplifier, the output from which actuated the ground noise reduction apparatus.

The filter which was necessary to eliminate the audio frequency ripple from the output of the rectifier necessarily produces a time delay commensurate with the lowest frequency which it is designed to filter out and this time delay produces a corresponding retardation of the response of the ground noise reduction mechanism. This necessarily produces a certain amount of clipping of the peaks of the waves when there is any rapid increase in signal amplitude.

In the present apparatus I decrease the adverse effects of the filter circuit and improve the operation of the apparatus by adding a volume compressor to the amplifier. The amplifier itself includes a tube of the variable gain type and the amplification is set at such a point that the application of compression is necessary to prevent over-amplification of the input signal. The compressor circuit itself is so designed that it has a time delay commensurate with, although not necessarily the same as, the filter circuit. The result of this arrangement is that when there is a sudden increase in signal it is transmitted by the amplifier at the gain for which the amplifier is set for the signal of lower amplitude thereby causing a rapid opening of the ground noise reduction shutter or other device

which minimizes the clipping of peaks. The compressor then comes into operation and decreases the amplification so as to provide only an appropriate margin during the steady state condition. Conversely, if there is a sudden decrease in the input signal strength, the compressor does not immediately change the amplification and if the signal then returns to its original strength no over-shooting or clipping of peaks occurs. This feature is particularly advantageous in the case of complex waves where the fundamental may have a very low frequency which the ordinary ground noise reduction amplifier would tend to follow while it may be quite rich in over tones which would normally actuate the usual ground noise reduction amplifier. In such a case the ordinary ground noise reduction amplifier tends to reduce the apparent amplitude of the fundamental while my improved amplifier permits the transmission of the signal substantially unchanged.

One object of the invention is to provide an improved ground noise reduction amplifier.

Another object of the invention is to provide an improved sound recording apparatus.

Another object of the invention is to provide a ground noise reduction amplifier with compression.

Another object is to provide an improved compressor circuit for a ground noise reduction amplifier.

Another object is to provide a ground noise reduction amplifier in which the time delay of the filter circuit is substantially compensated.

Other and incidental objects of the invention will be apparent to those skilled in the art from a reading of the following specification and an inspection of the accompanying drawing in which the single figure illustrates a commercial type of ground noise reduction amplifier with my improved compressor circuit applied thereto.

The amplifier itself is, in general, of commercial form and inasmuch as the resistor and capacitor values and tube types are indicated in the drawing no detailed description is necessary except insofar as the design is not commercial.

The audio frequency input is fed through the transformer 10 to the amplifier 11 which is of the variable gain type, and is provided with appropriate volume control devices. The output from the tube 11 is, in turn, fed to the amplifier 12, the output of which is fed through a transformer and remote control switch 15 to the rectifier 13. This rectifier 13 is slightly different from that usually used in that it is constructed

as described and claimed in Kellogg application Serial No. 237,603, filed October 29, 1938, Patent No. 2,227,906, issued Jan. 7, 1941.

The rectifier 13 charges the capacitors 17 and 18 simultaneously but these capacitors have different discharging times. The capacitor 17 discharges directly across the resistor 19 while the capacitor 18 discharges across the resistor 19 in series with the resistor 16. Therefore, the opening time of the ground noise reduction shutter is determined by the charging rate of the capacitor 18 while the closing time is determined by the discharge rate of the two capacitors in combination. The capacitor 18 obviously cannot discharge through the resistor 16 until the capacitor 17 has reached a lower voltage than the capacitor 18.

The output from this rectifier circuit is amplified by the D. C. amplifier tube 14, the plate current of which passes to the output circuit indicated, whence it is conducted to the ground noise reduction shutter or equivalent device.

A portion of the output of the audio amplifier 12 is directed through the lead 20 and the resistor 21 to the potentiometers 22 and 23. Appropriate amounts of the audio frequency current are taken off of the potentiometers 22 and 23 and applied through the capacitors 26 and 27 to the two rectifiers in the tube 40, the rectifier circuit being completed through the resistors 24 and 25. This rectifier tube 40 provides the bias for volume compression applied to the tube 11.

The cathodes of the rectifier 40 are connected to the biasing potentiometers 33 and 34 which provide an opposing bias in a manner and for a purpose described hereinafter, and the current passing through the portion of these potentiometers above the contact passes through the resistor 35 and is returned to the opposite end of the resistors 24 and 25. The current passing through the resistor 35 develops a potential across that resistor and across the capacitor 36 which potential is applied through the resistor 37 to the control grid 38 of the tube 11, where it serves to decrease the output of the tube on an increase in signal strength.

The current from the rectifier 40 also charges the capacitor 41 through the resistor 37 and through the upper portions of the potentiometers 33 and 34. The timing of the compressor circuit is therefore determined primarily by the values of the capacitors 36 and 41, the resistors 37 and 35, the upper portions of the potentiometers 33 and 34 and the resistors 24 and 25 in the order named. The upper portions of the potentiometers 33 and 34 and the resistor 37 affect principally the charging time of the capacitors 36 and 41, while the resistor 35 affects principally the discharge time thereof.

A positive potential is derived from the plate supply of the apparatus through the resistor 30, the resistor 31, and the resistor 32, and this positive potential is applied across the potentiometers 33 and 34. These potentiometers may be so adjusted as to develop any appropriate bucking potential opposing the passage of current through the two elements of the rectifier 40. No current will pass and, therefore, there will be no volume compression when the potential across the rectifier 40 is not greater than the minimum potential applied by either the potentiometers 33 and 34. As the potential applied to one of the rectifying elements reaches the mini-

5 mum opposing potential, current will begin to pass and develop the potential drop across the resistor 35, and cause the initiation of volume compression. As the volume input to the apparatus increases, the current through this portion of the rectifier will increase and at a predetermined point determined by the other potentiometer the other half of the rectifier will also start to pass current, thereby increasing the rate of increase of voltage drop across the resistor 35 with increase of input and determining the shape of the compression curve. Since the two potentiometers 33 and 34 are identical, either may be used to determine the minimum input at which compression will start and the other may be used to determine the shape of the compression curve.

In the normal operation of the amplifier the switch 50 remains in its upper position, as shown in the drawing. If it is desired to test the amplifier or to operate it for any other reason without having it connected to the normal output circuit, the switch 50 should be moved to the lower position thereby connecting the 760 ohm resistor 51 across the output. The resistor 51 has substantially the same resistance as the usual output load and therefore if this resistor is substituted for the output circuit the amplifier may be operated in its customary manner for the purpose of adjustment.

It will be apparent that there will be a certain amount of time delay not only in the input circuit to the rectifier 40 but also in the input through the potentiometers 33 and 34 to the capacitor 36 and the various delays in this compressor circuit may be so adjusted as to produce the most desirable timing effect in conjunction with the filter circuit in the output of the rectifier 13. The delay in the compressor circuit may be either greater or less than that in the filter circuit, and due consideration should also be given to the delays which occur between the amplifier tube and the rectifier in the audio frequency circuit. Insofar as I am now aware, the values of the several resistors and capacitors should be substantially as indicated in the drawing to produce the most desirable result in which the input signal is given time to initiate operation of the ground noise reduction apparatus just prior to the effect of the compression circuit on the first input tube.

Having now described my invention, I claim:

1. An amplifier including an A. C. amplifier, a rectifier, and a filter circuit, and a compressor circuit connected between the output and input of said A. C. amplifier, said compressor circuit having a time constant of the same order of magnitude as the said filter circuit.

2. A ground noise reduction amplifier including an audio frequency input circuit A. C. amplifier, a rectifier, a filter circuit, a D. C. amplifier and an output circuit from said D. C. amplifier for connection to ground noise reduction apparatus, and a compressor circuit connected between the output and input of said A. C. amplifier, said compressor circuit having a time constant of the same order of magnitude as the said filter circuit.

3. An A. C. to D. C. amplifier including an A. C. amplifier, a rectifier, a filter circuit, a D. C. amplifier, and a compressor circuit connected between the output and the input of said A. C. amplifier, said compressor circuit having a time constant of the same order of magnitude as the said filter circuit.

4. In combination with a signal input circuit, a filter provided with input and output circuits and a rectifier connected between said input circuits, a compressor circuit connected to said signal input circuit and having a time constant of the same order of magnitude as that of said filter, and means for adjusting both the dynamic characteristics and the time constant of said amplifier.

5. An amplifier including an A. C. amplifier, a rectifier, and a filter circuit, and a compressor circuit connected between the output and input of said A. C. amplifier, said compressor circuit including a rectifier circuit having a time constant of the same order of magnitude as the said filter circuit.

HERBERT BELAR.
